TRAVELING WAVE TUBE ELECTRODE MOUNTINGS**Edward C. Dench, Needham, Mass., assignor to Raytheon Company, a corporation of Delaware**

Filed Nov. 12, 1953, Ser. No. 391,628

27 Claims. (Cl. 315—3.5)

This invention relates to an electron gun mounting arrangement particularly adapted for use with a traveling wave electron discharge device and to such a device having a novel cathode for use with said electron gun.

Traveling wave electron discharge devices utilizing the interaction between an electron beam and one of the space harmonics of the RF wave traveling along a periodic frequency responsive delay line are well known. One embodiment of a traveling wave tube suited for generation of energy is shown and described in an application by E. C. Dench for U.S. Letters Patent, Serial No. 357,824, filed May 27, 1953. This tube includes a cylindrical periodic anode delay structure surrounding and concentrically arranged with respect to a negative electrode or sole, thus forming an arcuate interaction space. A heated cathode positioned adjacent the sole serves as a source of electrons. These electrons, under the combined influence of an electric field established between the anode and cathode and a magnetic field transverse to the electric field, are permitted to encircle the aforesaid interaction space, provided that the magnitude and polarity of the two mutually perpendicular fields are properly adjusted.

Improved operation may often be achieved by the use of an accelerator electrode positioned adjacent the emitting area of the cathode. This electrode, which is maintained at a positive potential relative to the cathode and sole, is instrumental in directing and shaping the electron beam prior to its entrance into the effective interaction space.

Furthermore, where modulation of a traveling wave tube oscillator is desired, a grid electrode may be provided adjacent the cathode in much the same manner that grids are utilized in receiving tubes. The grid serves to modulate the electron beam and thereby effects tuning of the oscillator.

The cathode assembly used with the traveling wave tube of the aforesaid copending application has characteristics which are not suitable for certain applications. Because the cathode in the aforesaid application is a directly heated ribbon of tungsten, the temperature for satisfactory emission is relatively high, being of the order of 2,300 degrees C. Due to the relatively large heating current flowing in directly heated cathodes of the prior art, the lead-in conductors must be of substantial size and the traveling wave tube must be capable of radiating a considerable amount of heat. The mean life of the directly heated tungsten cathode previously used in traveling wave tubes is approximately 200 hours thus necessitating frequent maintenance or replacement of tubes in associated equipment. This cathode, like all directly heated

2

cathodes, is productive of hum because of the voltage drop across the ribbon and may cause variations in the tube magnetic field.

One of the features of this invention is an improved cathode which comprises an elongated substantially polygonal block of porous tungsten coated with a layer of an emitting material which may, for example, contain a compound of barium. This block may be rectangular although the surface exposed to the interaction space should be substantially parallel thereto. For example, if a linear tube is contemplated, the surface of the cathode block adjacent the interaction space may be planar and parallel thereto. If the tube is circular, the surface of the cathode adjacent the anode or the interaction space may be slightly arcuate so as to be concentric with the anode. For many purposes, however, the rectangular cathode may be satisfactory even when used with a circular tube. The cathode contains an aperture in which a low voltage heater is inserted. This heater may be of folded construction, such as used in standard receiving tubes, in which case the effects of the stray magnetic field surrounding the heater may be substantially reduced. The heater may be coiled instead of folded construction. This cathode operates at a temperature of the order of 950 degrees C. as compared with 2,300 degrees C. for directly heated tungsten cathodes. Since the cathode is indirectly heated, hum troubles are minimized and the time required to reach a stable operating temperature is reduced. The increased emissivity of this cathode together with the lower operating temperature result in an average cathode life in excess of 2000 hours. The amount of heating power required is quite low, being less than ten watts under normal conditions. Because of the low heater current, smaller lead-in conductors may be used with resultant saving of space and weight of the traveling wave tube.

Another feature of this invention is an improved method of mounting the cathode, as well as other electrodes, if any, of the tube electron gun. Cathode mounting assemblies of the prior art have been comparatively bulky, complex and difficult to manufacture and assemble. Furthermore, in prior tubes utilizing an accelerator electrode, the latter is mounted on the inner rim of the anode by means of an insulator. The spacing between the cathode, which is supported from the sole, is subject to tolerances of both sole and anode and to variations in the relative positions of said sole and anode. This variation in spacing is undesirable since it has a direct effect upon the accelerating field, for a given accelerator voltage, and, consequently, affects the trajectory of the beam as it enters the interaction space.

Pursuant to this invention an electron gun mounting arrangement is obtained which may be easily and accurately assembled and which may readily be installed as a complete unit on the sole of the traveling wave tube. Each of the electrodes forming part of the electron gun is provided with supporting leads or rods fixedly attached to each electrode. These supporting leads are passed through apertures in a pair of spaced electrically insulating supports and protrude from the surface of said supports. These apertures are stamped out in a predetermined spaced relationship corresponding to the desired electrode array. The supports may be provided with metal eyelets which are inserted in the apertures and bent over at the edges. The supporting leads are then

secured to these eyelets, thereby supporting said electrodes in an accurate spaced relationship with one another. The insulating supports are then mounted to oppositely disposed portions of the sole structure. A portion of the sole may be cut away to accommodate the cathode heater and the grid and accelerating electrode, if any.

To prevent the undesirable formation of a conductive film on the surface of the insulating supports owing to the gradual evaporation of the emitting material from the cathode, a plate forming an extension of the sole flange and positioned over the electrode-containing slot in the sole may be used as an end shield. In tubes utilizing a grid, protection of the insulating supports from an accumulation of cathode material may alternatively be provided by means of end caps forming a part of the grid and positioned above the ends of the cathode. Since most of the evaporating emitter material moves toward the ends of said cathode, the grid caps need only cover the ends of the cathode body.

Fig. 8 is a fragmentary edgewise view of the modification of the mounting assembly of Figs. 6 and 7 minus the accelerating electrode;

Fig. 9 is a fragmentary plan view of the modification of Fig. 8; and

Fig. 10 is a detail view of a portion of the sole adjacent the mounting assembly of Figs. 8 and 9.

Referring now to Figs. 1 to 4, a traveling wave tube oscillator 20 is shown which includes a periodic, frequency responsive energy translation structure or anode delay line 22; a sole 30 maintained negative with respect to anode 22; a lead-in assembly 40; an output coupling means 50; an electron gun mounting assembly 60 further including at least a cathode 62 and heater 64 and a transverse magnetic field producing means, a portion of which is indicated in Fig. 1.

Anode assembly 22 comprises a circular interdigital delay line including a plurality of interdigital fingers 24 and 24' which extend from annular members 25 and 25', respectively. Members 25 and 25' are secured, as by screws 26 (see Fig. 2), to the shoulder portion of a cylindrical electrically conductive ring 27. The remainder of the anode assembly includes a pair of oppositely disposed cover plates 28 and 29 attached, as by welding, to ring 27.

The sole 30 consists essentially of a cylindrical block of metal, such as copper, having a recessed center portion 38 and a flange portion 39 and containing a plurality of apertures 31 extending through said recessed surface 38. A centrally located aperture 32 is provided in the sole to permit the connection of lead-in assembly 40 and the passage of external circuit connecting leads in a manner to be shown subsequently.

Lead-in assembly 40 includes a bipartite electrically conductive cylindrical tubular sleeve 42 which is inserted in an aperture in cover plate 28 of tube 20 and is welded or otherwise securely attached thereto. A section of

cylindrical glass tubing 43 serves to interconnect metal sleeve 42 and a second metal sleeve 44. The other end of sleeve 44 is provided with a glass seal 45 for sealing the electrical discharge device after evacuation. Sleeves 42 and 44 are preferably constructed of a material having an expansion coefficient closely approximating that of glass. The lead-in assembly is arranged perpendicular to cover 28 of tube 20 and further includes an elongated electrically conductive tubular supporting cylinder 46 which acts as the main support for sole 30 as well as for cathode mounting assembly 40. One end of cylinder 46 is affixed to the periphery of centrally located aperture 32 in sole 30. The other end of cylinder 46 contains an outwardly flared portion 47 which is connected to the inner surface of the second sleeve 44. The necessary cathode and heater leads are fed through supporting cylinder 46 and are insulatedly supported therefrom by glass beads 49.

The interdigital anode delay line 22 is arranged concentric with sole 30 and is separated from the circumferential wall 33 of the sole to form an interaction space 35 through which the electron beam generated by the cathode passes. Anode delay line 22 may be terminated at one end by attenuation, preferably in the form of an energy dissipative material, such as iron, which is applied to the fingers in the region over which attenuation is desired. The coaxial line 50 is sealed in an opening of wall 27 of the anode and impedance matched to the anode delay line.

30 The inner conductor 52 of coaxial output coupling means 50 is connected to a finger at or adjacent the end of the periodic anode delay line electrically remote from the attenuation region.

Traveling wave tube 20 may, in some cases, be provided with a collector electrode 37, shown in Fig. 2, for intercepting electrons after one traversal of the arcuate interaction space. This collector electrode preferably takes the form of a projection from the back wall of the anode delay line and is located adjacent the cathode. 35 The arrangement of this collector is shown in the aforesaid copending application.

Although the anode delay line has been described and illustrated as an interdigital delay line, this invention is not limited thereto. The anode delay line may, for example, consist of a loop-loaded wave guide, a strapped vane periodic structure, a strapped loop periodic structure or a disk loaded coaxial structure.

50 A suitable electric field between anode and sole may be obtained by means of a voltage applied between anode and sole. The sole may be negatively biased with respect to the cathode by means of a source 105 of voltage connected between cathode lead 48 and tubular conductor sleeve 46. The cathode may, however, be at the same potential as the sole, if so desired. Similarly anode 22 may be maintained at a positive potential relative to both sole and cathode by means of a source 107 of voltage connected between metal sleeves 42 and 44. Sleeve 42, by virtue of its electrical connection to cover plate 28, is at the same electrical potential as the anode.

60 A uniform magnetic field transverse to the direction of propagation of the electron beam is provided by either a permanent magnet or electromagnet having cylindrical pole pieces 80 and 81 radially positioned on or adjacent the tube. Pole piece 80 is apertured to receive the lead-in assembly 40 and pole piece 81 is apertured to maintain symmetry of the magnetic field. The flux lines should be concentrated in the interaction space 35 between sole 30 and cylindrical anode 22.

65 By proper adjustment of the magnitude and polarity of the magnetic and electric fields, the electron beam may be made to follow a circular path around interaction space 35 under the combined influence of the transversely disposed magnetic and electric fields previously referred to.

70 The radio frequency energy generated in the interaction

space 35 traveling along the anode periodic structure 22 sets up a high frequency electromagnetic field which may be analyzed as a series of space harmonics, some of which travel in one direction (clockwise) along the anode structure, and others of which travel counter-clockwise, and all of which travel with different phase velocities. If the electron beam, whose velocity is a function of the electric field strength, is synchronized with the proper space harmonic interaction of the beam, said space harmonic will result in the production of oscillations within the tube. The energy travels toward the electron source and is extracted at the cathode end of anode delay line 22 by way of coaxial output line 50.

The cathode mounting assembly 60 for the tube of Fig. 1 is shown in Figs. 3 and 4 and includes cathode 62 and heater 64, shown in detail in Fig. 4. The cathode 62 is in the form of a rectangular prism provided with a circular bore 63 in which a folded coated tungsten heater wire 64 is inserted. The heater may be of the type used in standard receiving tubes and may be connected at one end to the inner wall of the cathode. Cathode body 62 is preferably made of porous tungsten and the outer surfaces are coated with an emitter containing a compound of barium. This cathode not only is relatively small but operates at a relatively low temperature. For example, a typical cathode now in use is approximately 0.08 inch square and 0.8 inch long and operates at a temperature of approximately 950 degrees C. A corresponding directly heated cathode made of tungsten ribbon, such as used in the aforesaid copending application of Dench, operates at a temperature of approximately 2300 degrees C. A pair of molybdenum supporting leads 66 and 67 are spot welded to opposite ends of the cathode body, as shown in Fig. 4. By welding the leads at the ends of the cathode body, the heating effect is small and the barium emissive surface is not impaired. The cathode heater may, if desired, be connected to the supporting lead 66 at one end, as shown in Fig. 4. Although the supporting leads are preferably made of molybdenum, any electrically conductive material capable of withstanding temperatures of the order of 950 degrees C. may be used. The cathode body is positioned within a recess or slot 68 in wall 33 of sole 30, as shown in Fig. 3.

Mounting assembly 60 includes a pair of parallel mica insulating supports 70 and 71 containing a plurality of apertures 73, each of which receives a metallic eyelet 74. The cathode supporting leads 66 and 67 are welded to the eyelets in supports 70 and 71. One end of heater 64 is connected to cathode supporting lead 66 and the other end of the heater is connected to a stake 79, which is mounted in support 70 in the same manner as cathode supporting lead 66. Leads 66 and 67 should be good radiators of heat in order that the temperature drop between the cathode body at the point of attachment of the lead and the junction of the eyelet and the mica disk is a maximum. This is necessary in order to maintain the mica at temperatures below approximately 600 degrees C., at which temperature mica starts to disintegrate into powder. Molybdenum is a good heat radiator in addition to being a refractory metal. In order to further increase the heat radiation from the supporting leads, the metal may be roughened, as by sand blasting, and blackened. The mica insulating supports 70 and 71 are mounted to the sole by means of screws 76.

The insulating supports 70 and 71 need not be made of mica, however. For example, a ceramic may be used which, although not as resilient as mica to temperature changes, is capable of operation at higher temperatures. To allow for the smaller thermal expansion of the ceramic, however, it may be desirable not to weld lead 67 to the corresponding eyelet in support 71 but rather to allow it to slide freely within aperture 73 in support 71, as indicated in Fig. 5.

To prevent contact of the metal eyelets and the sole,

with consequent shorting of the various electrodes, the cathode and heater leads are insulated from the sole by means of spacers 78 located between the mica supports and the face of the sole. These spacers are preferably made of any material capable of withstanding heat. Although not essential, thin molybdenum sheets 75, such as shown in Fig. 7, may be positioned under the heads of each screw 76 in order to prevent possible damage to the mica supports resulting from pressure exerted by the heads of the metal screws.

In order to substantially reduce the strain on the cathode and heater resulting from connecting leads attached thereto, a pair of stakes 80 and 81 may be provided for the cathode and heater leads, respectively, and are secured to the mica insulating support 70 by eyelets, in the manner previously described. The stakes 80 and 81 are connected electrically to the protruding ends of the cathode supporting leads 66 and heater stake 79, respectively, by metallic cross bars 83 and 84, respectively.

It is often desirable to modulate a traveling wave oscillator by means of a grid electrode to which the modulating signal is applied. In addition, the use of an accelerating anode serves to permit the production of a more suitable electron beam trajectory. In Fig. 6 a modification of the mounting assembly of Fig. 3 is shown for use with traveling wave tubes having a grid 88 and an accelerating anode 90 in addition to the usual cathode and heater. Cathode 62 and heater 64 are mounted as in Fig. 3. Fig. 7 is an edgewise view of the assembly of Fig. 6 minus accelerating electrode 90.

Grid electrode 88 has a channel shaped portion 88' surrounding the cathode and an integral flat elongated portion 88" extending from the channel to provide increased heat dissipation from the grid. Grid 88 is mounted from mica insulating supports 70 and 71 by means of leads 91 and 92 attached at opposite ends of the grid, in the same manner that the cathode is mounted. Because of the configuration of the grid, a larger slot 68 must be provided than in the embodiment shown in Fig. 3.

Over a period of time, barium vapor accumulates on the mica supports of the mounting assembly of Figs. 1 and 3, owing to endwise evaporation from the cathode. This forms an electrically conductive film on the underside of the supports and eventually causes a short circuiting of the leads. In order to prevent this from occurring, end caps 98 are provided on the portion of the grid overlying the ends of the cathode to intercept the greater portion of the errant vapors, as shown in Fig. 6.

An accelerating electrode 90 is positioned adjacent the grid and cathode and includes a portion directly over the emitting area. The main portion 90' of the accelerating electrode is substantially parallel to the elongated portion 88' of grid 88. The parallel relationship of these portions of the grid and accelerating anode helps to maintain a proper electric field therebetween. Accelerating anode 90 also includes a tapered portion 90" which serves mainly to facilitate heat dissipation therefrom. This portion of the accelerating anode may be omitted, if desired.

In order to accommodate the accelerating electrode 90, which is laterally displaced from the grid cathode assembly, insulating supports 70 and 71 each comprise an extension to which the accelerator mounting leads 93 and 94 may be secured. A stake and cross bar may be provided for the grid and accelerating electrodes, just as for the cathode and heater, as shown clearly in Fig. 6. As in the case of the tube of Fig. 1, the various leads which connect to the stakes are brought through a lead-in assembly identical to that shown in Fig. 1, except that the number of leads is increased from two to four.

In Figs. 8 to 10 a modification of the electrode mounting assembly of Figs. 6 and 7 is shown. In lieu of

cathode and shields in the form of end caps 98 built on grid 88, a portion 99 of sole flange 39 is cut away, as shown in Fig. 10. An arcuate plate 100 is inserted within the slotted portion 99 and between the mica supports 70 and 71, as the case may be, and the ends of the cathode, as shown in Fig. 9. This plate is apertured to receive the electrode-supporting leads and heater lead as well as a pair of mounting screws 76. The thickness of plate 100 may be equal to the depth of cut in flange 39 of sole 30. Although the periphery of end plate of shield 100 is illustrated as being in alignment with the outer rim of sole flange 39, end plate 100 may extend outward beyond the periphery of sole 30, as in Fig. 6, in the event that an accelerating electrode is to form a part of the electrode assembly.

This invention is not limited to the particular details of construction, materials and processes described, as many equivalents will suggest themselves to those skilled in the art. For example, the mounting device described is not limited to use with tubes of cylindrical construction but may be applied equally as well to linear traveling wave tubes, such as shown and described in an application for U.S. Letters Patent of E. C. Dench, Serial No. 382,133, filed September 24, 1953. It is accordingly desired that the appended claims be given a broad interpretation commensurate with the scope of the invention within the art.

What is claimed is:

1. An electron source for a traveling wave tube having a periodic, frequency-responsive anode and a principal electrode arranged parallel thereto comprising an elongated substantially polygonal cathode body having at least one surface spaced from and parallel to said anode and containing an electron emitting material disposed on at least said one surface of said cathode body, and a heater positioned within the aperture in said body and spaced therefrom.

2. An electron source for a traveling wave tube having a periodic, frequency-responsive anode and a principal electrode arranged parallel thereto comprising an elongated porous cathode body positioned within a slot in said principal electrode and spaced from said anode, said cathode body further having a longitudinal aperture therein for receiving a heater, and an electron emitting material disposed on the surface of said cathode body.

3. An electron source comprising a porous cathode body having an aperture therein, a supporting lead connected to each end of said body, an electron emitting material disposed on the outer surface of said cathode body, and a heater positioned within the aperture in said body and spaced therefrom, one end only of said heater being connected to one of said supporting leads and the other end of said heater extending externally of said cathode body, said supporting leads having an irregular surface coated with a black material for increasing the heat radiation therefrom.

4. An electrode mounting assembly comprising an apertured cathode, a supporting lead connected to each end of said cathode, a heater positioned within said cathode, first and second spaced electrically insulating mounting members each having an aperture therein for receiving a supporting lead, said first mounting member further containing first and second rigid affixed electrically conductive elements, one end of said heater being electrically connected to said first element and the other end of said heater being connected to said one supporting lead, one of said supporting leads being electrically connected to said second element.

5. An electrode mounting assembly comprising an apertured cathode, a supporting lead connected to each end of said cathode, a heater positioned within and electrically insulated from said cathode, first and second spaced electrically insulating mounting members having apertures therein bounded by eyelets, one of said sup-

porting leads connected to and extending through said eyelet in said first member to form an electrical terminal, means including an electrically conductive element secured to said first member for connecting one end of said heater thereto.

6. An electrode mounting assembly comprising a base forming part of an electron tube, an apertured cathode, a supporting lead connected to each end of said cathode, a heater positioned within and electrically insulated from said cathode, first and second spaced electrically insulating mounting members having apertures therein bounded by eyelets, one of said supporting leads connected to and extending through said eyelet in said first member to form an electrical terminal, means including an electrically conductive element secured to said first member for connecting one end of said heater thereto, and means for attaching said mounting members to opposite portions of said base.

7. An electrode mounting assembly comprising an apertured cathode, a supporting lead connected to each end of said cathode, a heater positioned within said cathode, first and second spaced electrically insulating mounting members each having apertures therein for receiving a supporting lead, one of said supporting leads connected to and extending through said aperture in said first member to form an electrical terminal, the other of said supporting leads being adapted to move freely in said aperture in said second member, and means including an electrically conductive element secured to said first plate for connecting one end of said heater thereto.

8. An electrode mounting assembly comprising an apertured cathode, a grid partially surrounding said cathode, a supporting lead connected to each end of said cathode and said grid, a coil heater positioned within said cathode, first and second spaced electrically insulating members having apertures therein, one each of said supporting leads connected to and extending through said aperture in said first mounting member to form electrical terminals, means including an electrically conductive post secured to said first member for connecting one end of said heater thereto, said grid being provided with end caps positioned adjacent the ends of said cathode for preventing contamination of said first member by lateral emission from said cathode, and apertures within one of said end caps for insertion of said cathode supporting lead and said heater.

9. An electrode mounting assembly comprising an apertured cathode, a control electrode partially surrounding said cathode for controlling the current from said cathode, a supporting lead connected to each end of said cathode and said control electrode, a coil heater positioned within said cathode, first and second spaced electrically insulating mounting members having apertures therein bounded by eyelets, one each of said supporting leads connected to and extending through said eyelet in said first member to form electrical terminals, means including an electrically conductive post secured to said first member for connecting one end of said heater thereto, said control electrode being provided with end caps positioned adjacent the ends of said cathode for preventing contamination of said mounting members by lateral emission from said cathode, and apertures within one of said end caps for insertion of said cathode supporting lead and the ends of said heater.

10. An electrode mounting assembly comprising an apertured cathode, a control electrode partially surrounding said cathode for controlling the current from said cathode, and an accelerating electrode positioned adjacent said cathode and control electrode, a supporting lead connected to each end of said cathode, control electrode and accelerating electrode, a coil heater positioned within said cathode, first and second spaced electrically insulating mounting members having apertures therein bounded by eyelets, one each of said supporting leads

connected to and extending through said eyelet in said first member to form electrical terminals, means including an electrically conductive post secured to said first member for connecting one end of said heater thereto, said control electrode being provided with end caps positioned adjacent the ends of said cathode for preventing contamination of said mounting members by lateral emission from said cathode, and apertures within one of said end caps for insertion of said cathode supporting lead and said heater.

11. A traveling wave tube comprising a periodic frequency responsive energy translation structure for transmitting electromagnetic wave energy and constructed to produce adjacent thereto fields of the wave energy being transmitted, a principal electrode spaced from and substantially coextensive with said translation structure and maintained at a potential negative with respect thereto, a plurality of associated electrodes including a cathode for emitting electrons, and means for directing a beam of said electrons along the space between said structure and said principal electrode and in energy interacting relation with said fields, a pair of electrically insulating support members electrically insulated from and affixed to opposite portions of said principal electrode, a supporting lead connected to each end of each of said associated electrodes, said insulating support members containing apertures for receiving said supporting leads, and means for securing said supporting leads to said support members.

12. A traveling wave tube comprising a periodic frequency responsive energy translation structure for transmitting electromagnetic wave energy and constructed to produce adjacent thereto fields of the wave energy being transmitted, a principal electrode spaced from and substantially coextensive with said translation structure and maintained at a potential negative with respect thereto, a plurality of associated electrodes including a cathode for emitting electrons and a control electrode for controlling the electrons emitted from said cathode, and means for directing a beam of said electrons along the space between said structure and said principal electrode and in energy interacting relation with said fields, a pair of electrically insulating support members electrically insulated from and affixed to opposite portions of said principal electrode, a supporting lead connected to each end of each of said associated electrodes, said insulating support members containing apertures for receiving said supporting leads, an eyelet surrounding said apertures and affixed to said insulating support members, and means for securing said supporting leads to corresponding ones of said eyelets.

13. A traveling wave tube comprising a periodic frequency responsive energy translation structure for transmitting electromagnetic wave energy and constructed to produce adjacent thereto fields of the wave energy being transmitted, a principal electrode spaced from and substantially coextensive with said translation structure and maintained at a potential negative with respect thereto, a plurality of associated electrodes including a cathode for emitting electrons and an electron current control electrode partially surrounding said cathode, and means for directing a beam of said electrons along the space between said structure and said principal electrode and in energy interacting relation with said fields, a pair of electrically insulating support members electrically insulated from and affixed to opposite portions of said principal electrode, a supporting lead connected to each of said associated electrodes, said insulating support members containing apertures for receiving said supporting leads, an eyelet surrounding said apertures and affixed to said insulating support members, means for securing said supporting leads to corresponding ones of said eyelets, and means including a portion of said electron current control electrode for shielding said support members from said cathode.

14. A traveling wave tube comprising a periodic frequency responsive energy translation structure for trans-

mitting electromagnetic wave energy and constructed to produce adjacent thereto fields of the wave energy being transmitted, a principal electrode spaced from and substantially coextensive with said translation structure and maintained at a potential negative with respect thereto, a plurality of associated electrodes including a cathode for emitting electrons and a current control electrode partially surrounding said cathode, and means for directing a beam of said electrons along the space between said structure and said principal electrode and in energy interacting relation with said fields, a pair of electrically insulating support members electrically insulated from and fixedly mounted with respect to opposite portions of said principal electrode, a supporting lead connected to each end of each of said associated electrodes, said insulating support members containing apertures for receiving said supporting leads, an eyelet surrounding said apertures and affixed to said insulating support members, means for securing said supporting leads to corresponding ones of said eyelets, and means including a plate attached to said principal electrode for shielding said support members from said cathode.

15. An electrode mounting assembly comprising a cathode, a supporting lead connected to each end of said cathode, and first and second electrically insulating mounting members fixedly supported in spaced relationship, each of said supporting leads being supported by and extending through a corresponding one of said members.

16. An electrode mounting assembly comprising a cathode, a supporting lead connected to each end of said cathode, and first and second spaced electrically insulating mounting members each having apertures therein for receiving a corresponding supporting lead, one of said supporting leads extending through said aperture in said first member and secured to said first member to form an electrical terminal, the other of said supporting leads being adapted to move freely in said aperture in said second member.

17. An electrode mounting assembly comprising a cathode, a grid partially surrounding said cathode, a supporting lead connected to each end of said cathode and said grid, first and second spaced electrically insulating mounting members having apertures therein, one each of said supporting leads extending through a corresponding aperture in said first mounting member and supported by said first mounting member to form electrical terminals, said grid being provided with end caps positioned adjacent the ends of said cathode for preventing contamination of said first member by lateral emission from said cathode, and apertures within one of said caps for insertion of said cathode supporting lead.

18. An electrode mounting assembly comprising a cathode, a control electrode partially surrounding said cathode for controlling the current from said cathode, a supporting lead connected to at least one end of said cathode and said control electrode, at least one rigid support plate affixed in space, at least one electrically insulating mounting member electrically insulated from and maintained in spaced relationship with said support plate, said supporting leads being connected to said mounting member and extending through said support plate and said mounting member to form electrical terminals, said support plate being positioned to prevent contamination of said mounting member by lateral emission from said cathode.

19. A traveling wave tube comprising a periodic energy translation structure for transmitting electromagnetic wave energy and constructed to produce adjacent thereto fields of wave energy being transmitted, a principal electrode spaced from and substantially coextensive with said translation structure, a plurality of associated electrodes including a cathode for emitting electrons and an electron control electrode partially surrounding said cathode, means for directing a beam of said electrons along the space between said structure and said

principal electrode and in energy interacting relation with said fields, a pair of electrically insulating support members electrically insulated from and affixed to opposite portions of said principal electrode, a supporting lead connected to each end of each of said associated electrodes, said insulating support members containing apertures for receiving said supporting leads, and means for securing each of said supporting leads to said support members.

20. A traveling wave tube comprising a periodic energy translation structure for transmitting electromagnetic wave energy and constructed to produce adjacent thereto fields of wave energy being transmitted, a principal electrode spaced from and substantially coextensive with said translation structure, a plurality of associated electrodes including a cathode, for emitting electrons and an electron control electrode partially surrounding said cathode, means for directing a beam of said electrons along the space between said structure and said principal electrode and in energy interacting relation with said fields, a pair of electrically insulating support members electrically insulated from and affixed to opposite portions of said principal electrode, a supporting lead connected to each end of each of said associated electrodes, said insulating support members containing apertures for receiving said supporting leads, means for securing each of said supporting leads to said support members, and means including a portion of said control electrode for shielding said support members from lateral emission from said cathode.

21. A traveling wave tube comprising a periodic energy translation structure for transmitting electromagnetic wave energy and constructed to produce adjacent thereto fields of wave energy being transmitted, a principal electrode spaced from and substantially coextensive with said translation structure, a plurality of associated electrodes including a cathode for emitting electrons and a control electrode partially surrounding said cathode, means for directing a beam of said electrons along the space between said structure and said principal electrode and in energy interacting relation with said fields, at least one electrically insulating support member electrically insulated from and affixed to a portion of said principal electrode, at least one supporting lead connected to each of said associated electrodes, said insulating support member containing apertures for receiving said supporting leads, means for securing each of said supporting leads to said support member.

22. A traveling wave tube comprising a periodic energy translation structure for transmitting electromagnetic wave energy and constructed to produce adjacent thereto fields of wave energy being transmitted, a principal electrode spaced from and substantially coextensive with said translation structure, a plurality of associated electrodes including a cathode for emitting electrons and a control electrode partially surrounding said cathode, said cathode being apertured to receive a heater element, means for directing a beam of said electrons along the space between said structure and said principal electrode and in energy interacting relation with said fields, at least one electrically insulating support member electrically insulated from and affixed to a portion of said principal electrode, at least one supporting lead connected to each of said associated electrodes, said insulating support member containing apertures for receiving said supporting leads and said heater, means for securing each of said supporting leads to said support member.

23. A traveling wave tube comprising a periodic energy translation structure for transmitting electromagnetic wave energy and constructed to produce adjacent thereto fields of wave energy being transmitted, a principal electrode spaced from and substantially coextensive with said translation structure, a plurality of associated electrodes including a cathode for emitting electrons and a control electrode partially surrounding said cathode, means for

directing a beam of said electrons along the space between said structure and said principal electrode and in energy interacting relation with said field, at least one electrically insulating support member electrically insulated from and affixed to a portion of said principal electrode, at least one supporting lead connected to each of said associated electrodes, said insulating support member containing apertures for receiving said supporting leads, means for securing each of said supporting leads to said support member, and means including a portion of said control electrode for shielding said support member from lateral emission from said cathode.

24. A traveling wave tube comprising a periodic energy translation structure for transmitting electromagnetic wave energy and constructed to produce adjacent thereto fields of wave energy being transmitted, a principal electrode spaced from and substantially coextensive with said translation structure, a plurality of associated electrodes including a cathode for emitting electrons and a control electrode partially surrounding said cathode, said cathode being apertured to receive a heater element, means for directing a beam of said electrons along the space between said structure and said principal electrode and in energy interacting relation with said field, at least one electrically insulating support member electrically insulated from and affixed to a portion of said principal electrode, at least one supporting lead connected to each of said associated electrodes, said insulating support member containing apertures for receiving said supporting leads and said heater, means for securing each of said supporting leads to said support member, and means including a portion of said control electrode for shielding said support member from lateral emission from said cathode, said last-named means being apertured to permit passage of said heater element.

25. A traveling wave tube comprising a periodic energy translation structure for transmitting electromagnetic wave energy and constructed to produce adjacent thereto fields of wave energy being transmitted, a principal electrode spaced from and substantially coextensive with said translation structure, a plurality of associated electrodes including a cathode for emitting electrons and an electron control electrode partially surrounding said cathode, means for directing a beam of said electrons along a space between said structure and said principal electrode and in energy interacting relation with said field, a pair of rigid mounting plates adapted to be fixedly mounted to opposite portions of said principal electrode, a pair of electrically insulating support members electrically insulated from said mounting plates and mounted in spaced relation with respect to corresponding ones of said mounting plates, a supporting lead connected to each end of each of said associated electrodes, said insulating support members containing apertures for receiving said supporting leads, and means for securing said supporting leads to corresponding ones of said supporting members.

26. A traveling wave tube comprising a periodic energy translation structure for transmitting electromagnetic wave energy and constructed to produce adjacent thereto fields of wave energy being transmitted, a principal electrode spaced from and substantially coextensive with said translation structure, a plurality of associated electrodes including a cathode for emitting electrons and an electron control electrode partially surrounding said cathode, means for directing a beam of said electrons along a space between said structure and said principal electrode and in energy interacting relation with said field, at least one electrically insulating support member electrically insulated from and affixed to a portion of said principal electrode, at least one supporting lead connected to each of said associated electrodes, said insulating support member containing apertures for receiving said supporting leads, and means for securing each of said supporting leads to said support member.

27. A traveling wave tube comprising a periodic energy

13

translation structure for transmitting electromagnetic wave energy and constructed to produce adjacent thereto fields of wave energy being transmitted, a principal electrode spaced from and substantially coextensive with said translation structure, a plurality of associated electrodes including a cathode for emitting electrons and an electron control electrode partially surrounding said cathode, means for directing a beam of said electrons along a space between said structure and said principal electrode and in energy interacting relation with said fields, at least one electrically insulating support member electrically insulated from and affixed to a portion of said principal electrode, at least one supporting lead connected to each

14

5 of said associated electrodes, said insulating support member containing apertures for receiving said supporting leads, means for securing each of said supporting leads to said support member, and means including a portion 10 of said control electrode for shielding said support member from said cathode.

UNITED STATES PATENT OFFICE
CERTIFICATION OF CORRECTION

Patent No. 2,971,112

February 7, 1961

Edward C. Dench

It is hereby certified that error appears in the above numbered patent requiring correction and that the said Letters Patent should read as corrected below.

Column 8, lines 36 and 37, after "insulating" insert
-- mounting --; column 12, lines 24, 46, and 67, for "field",
each occurrence, read -- fields --.

Signed and sealed this 27th day of June 1961.

(SEAL)
